UNITED STATES PATENT OFFICE

JEAN MERCIER, OF PARIS, FRANCE

APPARATUS FOR THE DEPOLYMERIZATION OF HYDROCARBONS

Application filed December 13, 1928, Serial No. 325,724, and in France December 22, 1927.

The present invention relates to an improved plant for the depolymerization of hydrocarbons which are in the liquid state, or which may be converted into liquids or gases.

5 The principal features of the said plant will be specified in the following description.

In the appended drawings, which is given by way of example:

10 Figure 1 is a diagrammatic vertical section of a depolymerization plant, according to the invention, showing only the heating unit and one of the expansion and cooling units.

15 Figure 2 is a vertical section of a modification of an expansion and cooling unit, according to the invention, which comprises a set of vertical Field tubes.

20 Figure 3 is a diagrammatic vertical section of another modification of the expansion and cooling unit, which comprises a set of tubes of the Grille type.

Figure 4 is a perspective view of a modified construction showing another disposition of the retorts.

25 In the apparatus shown in Fig. 1, the hydrocarbons which consist of raw or residual hydrocarbons, such as fuel oil or heavy oils from coal, peat, naphtha, schist, lignite or the like, are vaporized by heating in a boiler A, of any suitable construction, or in any suitable vaporizer. The boiler may be an ordinary boiler, a tubular boiler or a coiled tube boiler.

25 The hydrocarbon may also be vaporized by the lower retorts of the unit B supplied with hydrocarbon in the liquid state provided said retorts are heated to a sufficient temperature.

30 In the unit B, which will be further described, the hydrocarbon vapours are depolymerized and said vapours are then passed through a regulating chamber C and a conduit D leading to the upper part of the first expanding and cooling unit E, which will be further described.

35 The condensed heavy oils are delivered from the bottom of the said expansion and cooling unit, and may be returned to the vaporizer A or otherwise used; the uncondensed vapours of oil or petrol (gasoline), which are also delivered from the bottom of

unit E through the pipe 17, may be sent into one or more following expansion units in which further fractional selections are effected, after which is disposed a condensing tower; said latter vapours may also be sent directly into the condensing tower, in which the last sorting takes place. The uncondensable gases are circulated through scrubbers and purifiers.

40 According to an embodiment of the invention, the heating unit B consists of a set of elementary retorts 1, carried by the frame 2 of the furnace. Said retorts 1 are superposed, and their longitudinal axes are inclined from the horizontal; they may have 45 any suitable cross section, and chiefly rectangular (the long axis of the section being vertical) which gives to the retort the shape of a beam of high resistance, while the absorbed heat is more efficiently distributed.

45 Coupling members 3 connect the several retorts in such manner as to form, from the intake of the vapours at 4, to their outlet at 5, a continuous retort of great length and comparatively reduced bulk, chiefly in height. 55

50 As shown, the coupling members may be disposed at the outside of the frame 2. In this case they are properly heat insulated from the atmosphere to prevent cooling of the vapours.

55 The retorts are filled with metallic scale or any other suitable catalyst 1^a, adapted to assist in the depolymerization of the hydrocarbons. The lower elementary retorts may contain a purifying substance, such as a sulphur-absorbing substance.

60 At the top part of the furnace is disposed an intake 6 for hot gas at a suitable temperature, supplied for instance by a fore-hearth and circulating downwardly. Baffles 7 are 65 provided in order to cause the gas to pass along the retorts, in the direction of their longitudinal axis and countercurrent to the direction of flow of the hydrocarbon vapours. At their outlet at 8, the burnt gases may be 70 circulated around the boiler A or any other recipient or boiler to be heated, so as to recover the sensible heat of said gases.

75 A regulating chamber C is preferably disposed at the top of the heating unit. Into 80

the lower part of said chamber opens a conduit 9 which leads from the uppermost retort to the upper part of said chamber, at a point remote from the conduit D connecting said chamber with the first expansion and cooling unit E. Said chamber, which is also filled with metallic scale or other catalyst, need not be heated. If necessary, the part 10 of the heating unit between said chamber and the uppermost retort may be heat insulated. A return conduit 10a leading back to the still or vaporizer A may be provided for the discharge of the liquids, which may have condensed.

15 The operation of the plant is as follows: The hydrocarbon vapours entering the bottom of the heating unit at a temperature from 300 to 400 degrees C., for instance, in the case of naphtha oil, will rise slowly through the 20 retorts, while being heated very gradually to about 500 degrees C., so as to prevent local overheating, which would at once cause cracking and, due to the carbon deposit, a clogging of the retorts.

25 The depolymerization of the hydrocarbons will thus take place very slowly; the metallic scale or like catalyst 1^a may in certain cases be disposed in such manner as to leave a free space 1^b adjacent the upper generators 30 in the elementary retorts, so that the lightest and hottest vapours will rise very readily and rapidly whilst the heavy vapours will remain for a longer time in the lower part of the retorts, in close contact with the catalyst.

35 The efficiency of the apparatus may be increased in some cases by a heat insulation 1^c on the upper portions of the retorts, so that the heating will only take place at the lower and lateral portions of the retorts, thus affecting the heaviest and coldest vapours, 40 whose depolymerization is thus furthered. This depolymerization is continued in the regulating chamber C, in which the heaviest and coldest vapours have a tendency to remain while expelling the lighter vapours.

45 Such a retort, in which the counterflow circulation secures an efficient transfer of heat has the advantage of providing a natural draught, allowing the lighter and hotter substances to issue more rapidly from the cycle 50 than the heavier and colder substances, which cannot be properly attained with horizontal retorts. It is superior to the vertical retorts by the fact that it is readily accessible and provides, for a given height a greater length 55 of retort, and hence an increased yield or capacity of treatment. The number of retorts mounted in parallel, may be considerably reduced, which is a great advantage for the obtaining of a regular operation because the 60 parallel arrangement causes irregularities in the proper distribution, which tend to be amplified when the apparatus becomes clogged up, since, as the speed of circulation 65 decreases, the temperature of the gas tends

to rise to the temperature of the heating unit structure, and this increases the clogging, due to the cracking effect.

Obviously, the arrangement of the retorts is not limited to that shown in Figure 1. 70 Thus, the combination of two adjacent rows of oblique retorts inversely inclined (Fig. 4) will permit, for a given height and only a double width, to place several series of retorts in parallel.

If it is desired to stir the vapours between two successive retorts, a baffle or deflector with restricted passages in each elbow may be provided. The adjacent retorts may also be connected by a coupling member which, 80 instead of being horizontal as shown in Figure 4, will cause the vapour to follow a short upward path. This arrangement also reduces the vertical bulk or height of the apparatus.

85 The expansion and cooling unit comprises a set of tubes, the cooling fluid being circulated through said tubes, which may be constructed in any suitable manner; for instance, the sets of tubes may be similar to 90 those employed in the tubular boilers of the Grille, Babcock, Field and other types.

95 By way of example, the expansion unit shown in Figure 1 comprises a set of oblique Field tubes, each consisting of an outer tube 11 connected to the outlet collector 12 for the cooling fluid, and an inner tube 13, connected to the inlet collector 14 for the admission of the cooling fluid. The cooling fluid which circulates through the tubes should have an intense cooling effect, in order that the surface of the tubes might be reduced, as much as possible, and the cooling action made as abrupt as possible.

100 The cooling fluid may consist of water, 105 which is raised to the boiling point when passing through the tubes, or of any other fluid, optionally under pressure.

110 The lower part of the expansion unit preferably consists of a regulating chamber 15 provided with the return conduit 16 for returning to the boiler the heavy products which have not been depolymerized. A conduit 17 connects chamber 15 with the top of the succeeding expansion unit or with the fractioning tower and opens within said chamber; 115 a wire gauze or screen 18 is adapted to prevent all obstruction of conduit 17 by the metallic scale or other catalyst contained in the cooling and expanding unit.

120 At the upper part is provided a cover 19, affording access to the interior of the apparatus. It is also observed that the tubes are readily accessible from the side. 19a denotes a conduit for the optional intake of return materials from the following apparatus, or of raw hydrocarbon oils from which petrol has not been removed.

125 The expansion unit above described affords a quick and abrupt cooling of the whole mass 130

of vapours in the presence of the catalyst, to an optimum temperature; due to the provision of the digester chamber 15, the hydrocarbon vapours will remain at said temperature for a certain time, whereby the equilibrium may be attained. By reason of this long stagnation, the vapours of ether and the gas may be again polymerized and may combine with the unstable substances delivered from the retorts. Furthermore, the cooling members or tubes occupy but a small space, thus leaving the maximum volume for the hydrocarbon vapours.

The condensation of the heavy substances disengages a sufficient amount of heat, to maintain the temperature substantially constant within the digester chamber 15, for example between 200 and 300 degrees C. in the case of naphtha. It may be desirable to provide a heat insulation at the lower part of the expansion unit.

The vapours which are not condensed in this first expansion and cooling unit may proceed into a second expansion and cooling unit or, if desired, it may be delivered at the bottom of the usual fractioning tower (not shown).

Fig. 2 shows a modification of the expansion and cooling unit in which the Field tubes are vertical, the regulating chamber being arranged at the top. The tubes 20 open at the upper end into an inlet collector 21, supplied with cold or hot water from a pipe 22.

The steam produced is discharged through a conduit 23, and may be utilized in a prime mover or as a heating medium. The hydrocarbon vapours enter through the conduit 24 and circulate downwardly around the tubes 20. Baffles 25 are preferably provided to slow up the circulation of the vapours and to keep them longer in contact with the tubes. The light vapours escape at the top at 26, while the condensed hydrocarbons are collected at 27.

Obviously, the gas may enter at the side of the apparatus. The cooling unit may also be filled with metal scale or other catalyst.

Fig. 3 shows another modification of the cooling and expanding unit, in which the set of tubes 28 is of the Grille type. The tubes are connected to an inlet collector 29, supplied for instance with cold water, and to an outlet collector 30 for the discharge of hot water. The vapours enter at 31 and are discharged at the bottom at 32, so that an inspection cover 33 may be provided at the top.

It is obvious that the vapours may also be circulated upwardly.

The gases which are not condensed in the plant, comprising the fractioning and scrubbing tower or towers, may be returned to any suitable part of the plant such as to the

vaporizer, heating unit or cooling and expanding unit, where they are again subjected to one or several steps of the cycle of operations.

In particular, when the gases contain a large proportion of methane, said gases, preferably after they are purified, may be circulated in a known manner over suitable substances at high temperature, so as to convert the methane into a mixture of hydrogen and non-saturated hydrocarbons. The gases thus treated are again introduced into the cycle, whereby the hydrogen and non-saturated hydrocarbons will combine with the vapours under treatment so as to finally increase the proportion of light liquid hydrocarbons similar to petrol.

Having now described my invention what I claim as new and desire to secure by Letters Patent is:

1. In an apparatus for the depolymerization of high boiling point hydrocarbon vapors, a heating unit comprising a hollow heat insulating frame, a set of superimposed inclined retorts mounted in said frame and connected together in series, means for supplying the lower retort with the material to be heated, discharge means connected to the uppermost retort for the escape of said material, means for supplying a heating medium into the hollow part of said frame, at the top thereof, an escape aperture for said medium at the bottom of the frame, deflecting means within said frame to oblige said heating medium to flow substantially along each individual retort, an unheated and heat insulating catalytic chamber provided at the top of said frame and interposed between the uppermost retort and the discharge means and in which the heavier vapors are condensed and means for the removal thereof from the condensate.

2. In an apparatus for the depolymerization of high boiling point hydrocarbon vapors, a heating unit comprising a hollow heat insulating frame, a plurality of superimposed retorts inclined and serially connected together so as to form an ascending channel for the material to be heated, means for supplying the lower retort with said material, discharge means connected to the uppermost retort for the escape of said material, baffles extending in the hollow part of the apparatus and defining together and with the walls of the frame a plurality of chambers serially connected end to end and each of which encloses one retort in such a manner that an annular channel is provided all round the retort and along the same between the chamber walls and the wall of said

retort, means for supplying a heating medium into the upper one of said chambers, and an escape aperture for said medium from the lower one of said chambers.

3. In an apparatus as claimed in claim 2, retorts having a flat and substantially rectangular cross-section with the great dimension vertically disposed.
5. In testimony whereof I have signed my name to this specification.

JEAN MERCIER.
